Atty.

UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

FOUR-HOLE SEW-ON BUTTON.

Application filed November 16, 1925. Serial No. 69,321.

To all whom it may concern:

Be it known that I, FRANKLIN R. WHITE, a citizen of the United States, residing at Waterbury, in the county of New Haven and State of Connecticut, have invented certain new and useful Improvements in Four-Hole Sew-On Buttons, of which the following is a specification.

My invention relates to new and useful improvements in four-hole buttons of the sew-on type and has for an object to design the hub of the button so that when the button is placed in an automatic button sewing machine, the button will be properly guided and controlled in its movement to the needle or needles and the four holes in the button will be directly in the path of the needle, so that the button may be readily attached to the garment.

The present application is a companion of four others filed by me of even date here-with, to wit, Serial Nos. 69,318; 69,319; 69,320 and 69,322.

As is well known to those skilled in the art, button attaching machines are provided with various mechanisms for properly centering and locating the buttons beneath the needles and the general practice is to use a button of the ordinary type.

The present button contemplates a special form of hub, so that the mechanism of the button attaching machine may be much more simple, as the shape of the hub causes the button to be centered and run down the chute to the needle of the machine.

With these and other objects in view, the invention consists in certain new and novel arrangements as will be hereinafter more fully described and pointed out in the claims.

Referring now to the drawings showing a preferred embodiment and a slightly modified form of the invention,

Fig. 1 is a top plan view of the button, the dotted line showing the shape of the outer end of the hub.

Fig. 2 is a sectional view taken on line 2—2 of Fig. 1.

Fig. 3 is a rear view of the button showing the square end of the hub and the location of the openings.

Fig. 4 is a plan view of a slightly modified form of button.

Fig. 5 is a sectional view taken on line 5—5 of Fig. 4, and

Fig. 6 is a rear view showing the hub 55 rounded at two edges and having parallel side walls merging with these edges.

Referring now more specifically to the drawings, and for the present to Figs. 1, 2 and 3, I have shown a button comprising 60 a body portion 1, the rim 2 and the button depressed centrally of its face as at 3. A hub 4 is shown centrally of the button, this hub being circular in outline where it merges with the body portion, but its periphery is 65 cut to form the side walls 5, 6, 7 and 8.

In other words the end of the hub is square, as may be seen in Fig. 3. This square-ended hub may be formed by initially forming the button with a round hub 70 and then cutting the sides, or the button may be made in a die and the four walls formed at the time the button is made.

The button may be made of wood, metal, 75 bone, shell, or other suitable material, the gist of the invention being the protruding square ended hub, so that the same may neatly fit within a chute or track and be guided in its movement. Also, an important feature of the invention is the location of 80 the holes 20 in the square ended hub, so that when the buttons are fed from a chute, not only will the button be properly guided in its movement, but the holes may properly register beneath the needle.

It will also be understood that inasmuch as the hub has the square end, the button may be in any one of four positions, as it is fed to the needle or needles.

Referring now to Fig. 3, there will be seen 90 the center point 9 on the surface of the hub, and if two lines are first drawn at right angles to each other and through the center point, it will divide the end into four squares. In each one of these parts there is provided a hole for the reception of a needle so that a thread may be passed through the garment and the holes to attach the button. These holes 20 are located centrally of the 95 aforementioned divisions and if additional diagonal lines be then drawn from the four corners, they will intersect the centers of these four holes.

By constructing a button in this manner,

the buttons may be placed in an automatic button attaching machine (not shown) and either set of parallel sides will center and guide the button in its movement as it passes down a cooperating chute to the needle or needles of the machine.

These automatic button machines are generally provided with a rotating hopper and as the holes are all in geometrical relation 10 and equi-distant from the center and sides, the buttons may register with the openings in the chute when in any of four positions and be properly and correctly guided and positioned to receive the needles when it 15 reaches the desired point beneath the needle.

In Figs. 4, 5 and 6 I have shown a slightly modified form in that there are only two parallel side walls, while the opposite ends 20 conform to the shape of the hub, or in other words, are arcuate.

This button comprises the body portion 10, rim 11, hub 12 and depressed central portion 13 on its outer face. The hub also has the 25 rounded ends 14 and 14' and is cut away at its sides to form the parallel side walls 15 and 16 as may be readily seen from Fig. 6.

The four holes 17 are provided, as may be seen in the several figures, and are in the 30 identical positions as shown in the preferred form, each center of the holes being equidistant from the center point 18 on the surface of the hub.

With a button of this type, the same may 35 be in one of two positions to pass into a chute, while the parallel side walls 15 and 16 will properly guide the button to the position below the needle and the holes, of course, will be in a registering position with 40 the needle.

This application is somewhat similar to a companion case, bearing Serial Number 69,322.

From the foregoing it will be seen that 45 I have provided a button which is relatively cheap to manufacture, and may be made

to cooperate with more simple mechanism of a button attaching machine than is now in use.

Many slight changes might be made without in any way departing from the spirit and scope of the invention.

Having thus described my invention, what I claim as new and desire to secure by Letters Patent is:—

1. A four-hole sew-on button comprising a body portion, a depending hub, said depending hub having at least two parallel faces opposite each other, the said hub provided with four holes, all arranged equidistant from the central point on the end of the hub and two holes adjacent each parallel side, and the said parallel sides adapted to properly guide and locate the button in a button attaching machine. 60

2. A four-hole sew-on button comprising a body portion, a depending hub, said hub being reduced at its end to form the hub square in outline, the hub having four holes extending therethrough and arranged so that if diagonal lines are drawn from the corners of the square, each line will intersect the center of two of said holes, and the square-ended hub adapted to center and guide the button in its movement to the needle of an automatic button sewing machine. 70

3. A four-hole sew-on button comprising a body portion, a square-ended hub, said hub provided with four holes therethrough and arranged equidistant from a central point on the end of the hub, and two holes located adjacent all four sides of the square and the said square-ended hub adapted to permit the button to assume one of four positions in a button attaching machine and to guide the button in its path to the needle of the said machine. 80

In testimony whereof I affix my signature.

FRANKLIN R. WHITE.
